UNITED STATES PATENT OFFICE.

JACOB K. NISSLEY, JACOB S. MUMMA, AND JACOB HOSTETTER, OF FLORIN, PENNSYLVANIA, AND JOSHUA W. HARRIS, OF STAUNTON, VIRGINIA.

TRANSPLANTER.

SPECIFICATION forming part of Letters Patent No. 411,225, dated September 17, 1889.

Application filed February 23, 1889. Serial No. 300,972. (No model.)

To all whom it may concern:

Be it known that we, JACOB K. NISSLEY, JACOB S. MUMMA, and JACOB HOSTETTER, of Florin, in the county of Lancaster and State of Pennsylvania, and JOSHUA W. HARRIS, of Staunton, in the county of Augusta and State of Virginia, have invented a new and useful Improvement in Transplanters, of which the following is a specification.

10 The invention consists in an improved transplanter, being an improvement on the invention for which Letters Patent No. 340,211 were obtained April 20, 1886, and the new and improved transplanter will be hereinafter fully 15 described and claimed.

Referring to the accompanying drawings, Figure 1 is a perspective view of the improved transplanter. Fig. 2 is a side view showing the single operating-lever depressed and the 20 shovels thereby opened and the coverers or hoes closed. Fig. 3 is a perspective view taken from the other side; and Fig. 4 is a sectional view on line *x x*, Fig. 2.

The same letters of reference indicate 25 corresponding parts in all the figures.

Referring to the several parts by letter, A indicates the casing of the transplanter, which is provided at its upper end with the stationary handle A' for the left hand of the operator. To the lower end of the casing A are hinged, opposite to each other, the shovels or 30 planters B B, having near their upper ends the extensions B' B', to the outer ends of which are hinged the lower ends of the connecting-rods C C. The upper end of the left-hand connecting-rod C is pivoted to the free end of the left arm D' of a short crank-rod D, which passes through bearings at the upper end of casing A, as shown, while the other 35 end of the said shaft has a bifurcated or V-shaped arm D², to the free end of the lower part of which the upper end of the right-hand connecting-rod C is bolted.

E E indicate the hoes or coverers, which 40 are hinged to the lower end of the casing A, at which point are bolted to the lower end of the casing re-enforcing metal plates *a a*, which serve the important function of greatly strengthening the lower end of the casing at 45 the point where the hinges *e e* are bolted to

it. The hoes have crank-arms E', to the free ends of which are hinged the lower ends of connecting-rods F F, the upper end of the connecting-rods being pivoted to the free ends of the arms G' and G² of a short crank-rod G, 55 which passes through bearings at the upper end of the casing A, as shown. To the extended free end of the arm G² is secured one end of a coil-spring H, the lower end of which is affixed to the casing A, this spring operating to normally draw the arms G' G² down and hold the coverers or hoes open.

Inside of the casing A is secured a tube or feeder I, the upper end or mouth-piece I' of which flares out to both sides, as shown, so 65 that it can be fed either by the operator or by a second person on the other side of the transplanter.

Upon the right-hand end of the rod G, between the side of the casing A and the arm G², is pivotally mounted the single operating-handle J. The lower end of this handle, below its pivotal point, extends under the free end of the upper arm of the V-shaped arm D², while upon this lower end of the lever is 70 formed an outwardly-projecting lug J', which extends out under the arm G², as shown. A coil-spring K, connected to the arm D² and the side of the casing, serves to draw the arms D' and D² down, and normally hold the 75 shovels or planters closed.

To the side of the casing A is bolted by its lower end a spring catch or lock L, which at its upper extremity bears against the lower end of the operating-handle J, while the upper part of the spring is curved out in a half-circle at L', as shown.

To the lower end of the casing A, at one corner thereof, is bolted a plunger-rod M, preferably shod with metal at its point.

In operation, the lower end of rod M is plunged into the ground, and serves to steady the transplanter in operation. The tobacco plant being placed in the tube I and the closed point of the shovels being thrust into the 95 ground, the operator, holding the handle A' in his left hand, pushes down the operating lever or handle J with his right hand. As the lower end of the operating-handle extends under the upper half of the V-shaped arm D², 100

it will be seen that when the handle is pressed down the arms D' and D^2 of the rod D will be raised, thus through the connecting-rods $C\ C$ opening or separating the hinged shovels B 5 B , and dropping the plant in the opening thus made. A moment after the shovels begin to open the lug J , coming in contact with the arm G^2 , will raise the arms G' and G^2 of the rod G , and thus through the connecting-rods $F\ F$ 10 press the coverers or hoes $E\ E$ in toward each other, pressing the earth in firmly above the root of the plant. As the operating-handle is thus depressed, a stop b preventing its being thrown down too far, the free end of the lower arm of the V-shaped arm D^2 , which is rounded on its upper side, 15 forces the upper end of the spring-catch L out until the end of the arm passes above the shoulder L^2 , formed by the curved upper end 20 of the spring, when it is held by the said shoulder, and the lever is thus locked in its depressed position and the transplanter is lifted out of the ground in this position. Inside of the shovels $B\ B$ are bolted by their 25 upper ends to the inner side of the lower end of the casing A , spring guard-arms $N\ N$, as shown in the sectional view Fig. 4 of the drawings, which, it will be seen, will prevent the earth from falling in on the heart of the 30 plant, holding the plant erect as the machine is being lifted, this being an important feature of our invention.

The transplanter being lifted out of the ground with the operating-lever locked in its 35 depressed position, as above described, the operator raises the handle J , when the lower

end of the handle will push out the upper end of spring-lock L until the shoulder L^2 is free from the end of the arm D^2 , when the coiled spring will restore the parts to their 40 normal position, closing the shovels and opening the coverers or hoes ready for the next plant.

It will be seen that the invention is simple and strong in construction, and rapid and 45 very efficient in its operation.

Having thus described our invention, what we claim, and desire to secure by Letters Patent, is—

1. The combination, with the casing and 50 the feed-tube, of the hinged shovels, the hinged coverers, the connecting-rods, the rods having the crank-arms and the single operating-lever, substantially as set forth.

2. In a transplanter, the combination, with 55 the casing and the hinged shovels, of the spring guard-arms, arranged substantially as set forth.

3. The combination, with the casing and 60 the feed-tube, of the hinged shovels, the hinged coverers, the connecting-rods, the rods having the crank-arms, the coil-springs, the single operating-handle, and the spring-catch, substantially as set forth.
